CLAIM

The ornamental design for a loudspeaker, as shown and described.

DESCRIPTION

FIG. 1 is a front perspective view of a loudspeaker showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a bottom view thereof;

FIG. 7 is a top view thereof;

FIG. 8 is a cross-sectional view thereof, taken along line 8-8 of FIG. 2;

FIG. 9 is a cross-sectional view thereof, taken along line 9-9 of FIG. 2;

FIG. 10 is a cross-sectional view thereof, taken along line 8-8 of FIG. 2, with unclaimed portions omitted for clarity; and,

FIG. 11 is a cross-sectional view thereof, taken along line 9-9 of FIG. 2, with unclaimed portions omitted for clarity. The broken lines illustrate portions of the loudspeaker that form no part of the claimed design.
